(57) **CLAIM**

The ornamental design for faucet, as shown and described.

DESCRIPTION

FIG. 1 is a perspective view of our new design for a faucet; FIG. 2 is a rear elevational view of our new design for the faucet;

FIG. 3 is a front elevational view of our new design for the faucet;

FIG. 4 is a bottom plan view of our new design for the faucet;

FIG. 5 is a top plan view of our new design for the faucet; FIG. 6 is a left side elevational view of our new design for the faucet viewed from the side opposite the handle socket; and,

FIG. 7 is a right side elevational view of our new design for the faucet viewed from the handle socket side.

The handle for the faucet is not shown in any of the drawings and forms no part of the claimed design.
